UNITED STATES PATENT OFFICE.

RALPH E. WILLIAMS, OF SANTA ANA, CALIFORNIA, ASSIGNOR TO WILLIAMS MANUFACTURING COMPANY, A CORPORATION OF CALIFORNIA.

SPOTLIGHT BRACKET.

Application filed September 17, 1917. Serial No. 191,840.

To all whom it may concern:

Be it known that I, RALPH E. WILLIAMS, a citizen of the United States, residing at Santa Ana, in the county of Orange, State of California, have invented new and useful Improvements in Spotlight Brackets, of which the following is a specification.

This invention relates to brackets or supporting means for adjustable headlights for automobiles, commonly known as spot-lights, and it is an object of this invention to provide a bracket or mounting means for a spot-light including a means for preventing the spot-light from being raised beyond a certain angle while directed on the road.

In order to avoid the throwing of a blinding light into the eyes of an approaching automobile or person, it is desirable, and in some communities is enforced by law, to prevent a spot-light from being raised above a certain angle or level on the road; yet it is desirable to have the spot-light so mounted that, if it is turned off the road, it may be thrown upwardly when, for instance, the driver wishes

to turn the spot-light upon a sign post.

It is an object of this invention to provide a bracket which will at once comply with the law and with best usage, and still will not detract from the utility of the spot-light. It is also an object to provide a bracket convenient and simple in form and easily operated and set in any desired position. It is also an object of this invention to provide a lamp which may, at any time, be turned down for inspection of the motor or anything in front or below the lamp, and may be clamped on oval, square, half-round and rectangular windshield frames of any character. Further objects will appear from the following specification wherein I explain in detail a form of my invention; reference for this purpose being had to the accompanying drawings in which—

Fig. 1 is a plan of my improved bracket; Fig. 2 is a section taken as indicated by line 2—2 on Fig. 1; and Fig. 3 is a horizontal section taken as indicated by line 3—3 on Fig. 2.

In the drawing the numeral 10 designates the bracket member which is adapted to be attached to the windshield of an automobile; having for this purpose two clamp pieces 11 and 12 having on their inner opposing faces concaved parts 13 and square surfaced parts 14, for the purpose of fitting

upon a wind-shield frame either circular, oval or rectangular in cross section. These two clamp members are held together by any suitable means, as by a screw 15. The member 11 carries in its outer end a vertical pivot socket 16, equipped with the usual clamping screw 17 for holding the pivot shaft 18 immovable. The pivot shaft 18 carries on its upper end the lamp carrying member 19. This lamp carrying member 19 has a shank 20 which carries the horizontal pivot shaft 21 at its end, this horizontal pivot shaft 21 being held in the horizontal socket 22 forming a part of the mounting member 23 which is mounted directly upon the vertical pivot shaft 18. The socket 22 is provided with the clamp screw 24 to set the shaft 21 in any desired position, and thereby to hold the lamp carrying member 19 immovable. The lamp carrying member 19 carries the usual lamp 25, reflector 26, and receptacle switch 27, all of which may be of the usual design and need no particular description here.

The bracket member 11, which is relatively immovable, has a part 11^a provided with two screw threaded holes 27 in either one of which a stop screw 28 may be placed. This stop screw 28 is adjustable in vertical position and is provided with a lock nut 29 to lock it in any position adjusted for height. The horizontal pivot shaft 21 has a part 21^a that projects out beyond the socket 22 and projects over the position of stop screw 28; and this portion 21^a is semi-cylindrical and hollow underneath; so that a concavity is presented at 21^b between two shoulders 21^c which face downwardly at the opposite edges of this semi-cylindrical portion. When the whole device is in a position with the light from the lamp 25 thrown straight ahead, or approximately straight ahead, then one of the shoulders 21^c will strike the head of the stop-screw 28 if the lamp carrier member 19 is turned on the horizontal pivot shaft 21 beyond a certain position. The stop screw 28 may be adjusted so that the lamp cannot be raised any higher than good usage dictates or the law permits. The device is shown in the drawings in its arrangement to be attached at the right hand side of a windshield; if it is attached at the left-hand side of the windshield, the device is turned over and the stop screw is put in the other screw thread.

ed hole 27, where it again accomplishes its object. Now, if the lamp is turned to one side about the vertical pivot shaft 18 enough to throw the light off the road ahead, then 5 the shaft part 21^a is thrown around to such a position relative to the stop screw; and the light may then be thrown upwardly as well as downwardly. If the lamp carrying member 19 is turned in the direction indicated by the arrow in Fig. 1, then the concave part 21^b straddles the stop screw, and the two shoulders 21^c then move on opposite sides of the stop screw, but clear of it. If the lamp carrying member 19 is turned 10 in the other direction, opposite to that indicated by the arrow in Fig. 1, then the shaft part 21^a entirely clears the stop screw; and in either case the lamp may be turned upwardly by a sufficient amount for all purposes. It will be noted that the part 21^a of the shaft 21 is on the opposite side of the center of vertical pivot shaft 18 from the lamp carrying member 19 so that movement 15 of the lamp carrying member in the direction indicated in Fig. 1 will cause the movement of part 21^a in the direction indicated in that figure.

Having described a preferred form of my invention, I claim:

30 1. In an adjustable headlight, a mounting bracket, a mounting member on a vertical pivot on the bracket, a horizontal pivot socket on the mounting member, a horizontal pivot shaft in said socket, a lamp carrying member rigidly carried on the pivot shaft, said shaft having on its end a semi-cylindri-

cal hollow portion concave beneath, stop carrying means on the bracket beneath each edge of the said shaft portion, and a stop which may be placed in either carrying means to be struck by either edge of the said shaft portion, the hollow being adapted to straddle the stop when the lamp carrying member is turned away from a normal central position.

40
45

2. In an adjustable headlight, a mounting bracket, a mounting member on a vertical pivot on the bracket, a horizontal pivot shaft revoluble in the mounting member and carrying a lamp, said shaft having two lugs spaced transversely of the shaft, stop carrying means on the bracket beneath each of the spaced lugs, and a stop which may be placed in either of the carrying means to be engaged by either of the lugs.

50
55

3. In an adjustable headlight, a mounting bracket, a mounting member on a vertical pivot on the bracket, a horizontal pivot shaft revoluble in the mounting member and carrying a lamp, said shaft having two lugs spaced transversely of the shaft, and changeable stop means on the bracket that may be changed between positions where it lies beneath either one or the other of the shaft lugs.

65

In witness that I claim the foregoing I have hereunto subscribed my name this 7th day of September 1917.

RALPH E. WILLIAMS.
